Fig. 1

Fig. 2

Fig. 1 is a plan view of a handbag or similar article showing my new design.

Fig. 2 is an edge view thereof.

The back portion of the handbag or similar article is substantially the same as that shown in Fig. 1.

The textured pattern on the upper right hand quarter as shown in Fig. 1, is repeated throughout the surface of the handbag.

I claim:

The ornamental design for a handbag or similar article, substantially as shown and described.
